Primary Examiner — Ramzi S Almatrahi(74) *Attorney, Agent, or Firm* — Wolf, Greenfield & Sacks, P.C.(57) **CLAIM**

The ornamental design for a camera, as shown and described.

DESCRIPTION

FIG. 1 is a top, front, and left side perspective view of a camera showing my new design;
FIG. 2 is a top, front, and right side perspective view thereof;
FIG. 3 is a top, rear, and right side perspective view thereof;
FIG. 4 is a front perspective view thereof;
FIG. 5 is a rear perspective view thereof;
FIG. 6 is a left side perspective view thereof;
FIG. 7 is a right side perspective view thereof;
FIG. 8 is a top plan view thereof; and,
FIG. 9 is a bottom plan view thereof.

The broken lines depict portions of the camera in which the design is embodied that form no part of the claimed design.
